TEXTILE FABRIC

William Colvin, Jr., Troy, N. Y.

Application July 30, 1930, Serial No. 471,758

8 Claims. (Cl. 139—425)

This invention relates to improvements in fabric.

The primary object of this invention is the provision of an improved textile fabric which is provided with metallic threads, such as of copper, in an improved relation; providing a fabric which is particularly well adapted to be used for a great variety of purposes, such as for screens, radio antennas, or for use in connection with phototone and television work, and which may find efficient use in connection with millinery, hairdressing, electrical heating pads and clothing pads, and which on a largely modified scale, may be found efficient in connection with the reinforcement of cementitious structures.

Other objects and advantages of this invention will be apparent during the course of the following detailed description.

In the accompanying drawing, forming a part of this specification, and wherein similar reference characters designate corresponding parts throughout the several views,

Figure 1 is a face view of the improved fabric, showing the improved relation of warp and weft yarns and the relation by means of which they are tied together.

Figure 2 is a view of the reverse side of the fabric of Figure 1, turned from left to right.

Figure 3 is an enlarged view showing the relation of the warp to weft or filler yarns.

In the drawing, wherein for the purpose of illustration is shown only a preferred embodiment of the invention, the letter A may generally designate the improved textile fabric, which is preferably composed of metallic warp threads 10 arranged in definitely spaced parallelism, with which are cooperatively associated the fabric weft threads or yarns 11, tied in upon the warp strands 10 by means of threads 12 which spirally and individually encompass each of the warp threads 10, in an improved cooperative relation therewith.

In view of the intended use of the fabric, it is essentially porous, since the main use will be in connection with radio art, as screening or antenna fabric, although the improved fabric of this invention is particularly well adapted for use as curtain material and wherever screening or fabric is desirable for use in interior decorating; the fabric being particularly well adapted for such use due to a certain inherent tendency which the same possesses to maintain its original shape, and the ease with which it may be made to assume a definite shape or form.

The entire warp is preferably made of the metal-

lic threads or strands 10, which are preferably of electrical conductive material, such as copper, which may be coated or covered by means of enameled or cotton-winding the same, or enclosing the same in insulation of any approved nature. The material of the wire warp strands is not to be limited to copper, since it is entirely feasible to use any desirable alloy or metal to serve a particular purpose; it even being within the contemplation of the invention to use silver. Under certain circumstances the warp strands may be left uncovered. However, in the preferred instance, as shown in Figure 3, I elect to cover the wire body 15^a of the strands 10, with an insulation coating 16 which may be of any approved nature. I have found it most economical to use ordinary cotton-wound copper wire, and the same may be liquid-coated or impregnated.

The weft yarns 11 may be of any approved nature, preferably of fibrous material, such as cotton, rayon, silk, worsted, or any other material. In the preferred instance the weft yarns 11 are each made of a plurality of untwisted parallel strands, such as shown in Figure 3 of the drawing, which are properly tied in and interwoven with the warp wires by means of the spirally wound tying-in threads 12.

The weft yarns 11 are each woven in parallel lengths between the warp wires 10, in the relation shown in the drawing. That is, as more clearly shown in Figure 3, each weft yarn 11 extends in a plurality of parallel lengths 17^a and 17^b, sinuously laid back and forth across the spaces between three of the adjacent wire strands 10; the strands 17^a and 17^b all crossing to one side of the intermediate strand 10, as shown in Figure 3, and the bight portions 18, connecting the lengths 17^a and 17^b, terminating at the wire strands 10 immediately adjacent and at opposite sides of that strand 10 across which the lengths 17^a and 17^b extend; these bight portions 18 being each tied in to the adjacent wire warp thread or strand by means of a spirally wound tied-in thread 12. It is thus to be noted that the sinuously wound filler or weft yarns 11 all cross the respective wire strands 10 at one side of the fabric, as is best shown in Figure 1, and the wire strands 10 stand more prominently exposed at the opposite side, as is best shown in Figure 2. The side of the fabric shown in Figure 1 is the "right" side and it is to be particularly noted that the tie-in yarns 12 are so positioned as to engage thru the bight portions or loops 18 of adjacent filler threads 11 from the upper part of the loop of one bight to the lower part of the

loop of another, in crossing relation with the adjacently related lengths 17^b, as clearly shown in Figure 3. Thus, the tie-in yarns do not tie-in the lengths 17^a, which due to the crowded nature 5 of the weft, work themselves out on top and the effect of which is to hide or rather secrete the tie-in yarns 12 and the adjacent tie-in portions of the warp and weft yarns. This is especially true since the untwisted strands making up the 10 weft yarns or threads 11 will "fluff" at the "right" side of the fabric. This effect is not so pronounced as is shown in the drawing, due to difficulty in proper illustration. The tie-in yarns 12 are quite inconspicuous, due to the fact that 15 they are of small size compared to either the warp or weft yarns, and the relation as to size between the yarns is somewhat of the nature shown in Figure 3.

The sinuously inter-related weft threads may 20 be suitably tied in along the selvage or edges of the fabric, as can quite readily be understood, and in connection with use of the improved textile fabric for radio antenna and screening use, the warp wires may be conductively connected 25 together.

It is to be particularly noted that the textile fabric is rather loosely made, and the spacing of the lengths making up the weft yarns is appreciably closer than the spacing of the wire warp 30 threads. The wire warp threads are of course conductive and flexible, and inherently more rigid than the fibrous weft and tie-in yarns, as can quite readily be appreciated.

Various changes in the shape, size, and arrangement of parts may be made to the form of invention herein shown and described, without departing from the spirit of the invention or the scope of the claims.

I claim:

40 1. Fabric of the class described composed of warp threads of flexible metallic wire and fibrous untwisted weft threads connected therewith and each composed of a plurality of substantially paralleling individual strands of material all disposed upon the same side of the warp threads.

2. Fabric of the class described composed of a warp made up entirely of wire electrically conductive material and a filler connected therewith and made up entirely of loosely spaced

50

3. Fabric of the class described composed of a warp made up entirely of wire electrically conductive material and a filler connected therewith and made up entirely of loosely spaced

55

4. Fabric of the class described composed of a warp made up entirely of wire electrically conductive material and a filler connected therewith and made up entirely of loosely spaced

60

5. Fabric of the class described composed of a warp made up entirely of wire electrically conductive material and a filler connected therewith and made up entirely of loosely spaced

65

6. Fabric of the class described composed of a warp made up entirely of wire electrically conductive material and a filler connected therewith and made up entirely of loosely spaced

70

7. Fabric of the class described composed of a warp made up entirely of wire electrically conductive material and a filler connected therewith and made up entirely of loosely spaced

75

fibrous textile yarns disposed upon one side only of the warp.

3. Fabric composed of warp wires in appreciably spaced relation, sinuously wound filler yarns of fibrous material centralized in adjacent pairs of spaces between the warp wires and means connecting said warp wires and the bight portions of the filler wires. 80

4. Fabric composed of warp wires in appreciably spaced relation, sinuously wound filler yarns of fibrous material in adjacent pairs of spaces between the warp wires, each weft length of the same being tied in with the alternate warp wires at the bight portions of the filler yarn lengths, each length of weft between the bight portions thereof crossing a warp wire between the spaces across which the respective filler yarns extend. 85

5. Fabric composed of warp wires in appreciably spaced relation, sinuously wound filler yarns of fibrous material in adjacent pairs of spaces between the warp wires, each length of weft between the bight portions thereof crossing a warp wire between the spaces across which the respective filler yarns extend, and means for tying the bight portions of the weft filler yarns, 90

the warp wires and also the intermediate portions 100

of alternate lengths of the filler yarns to the adjacent warp wires, the remaining lengths of the filler yarns free floating between their ends across said warp wires. 105

6. A textile fabric composed of warp wires, sinuously positioned fibrous filler threads each crossing certain of the warp wires, and fibrous tying threads spirally wound around said warp wires and interconnected in the bights of the 110

sinuously wound filler threads and tying them in against said warp wires.

7. Fabric comprising a wire warp, a fibrous

filler, and fibrous tying in yarns spirally wound

115 around the warp wires for connecting the fibrous filler therewith.

8. Fabric composed of insulation covered electrically conductive wire strands running in one direction, and non-metallic fibrous yarns extending transverse thereto and all crossing the wire 120 strands on the same side of each wire strand, and means connecting said yarns therewith.
